UNITED STATES PATENT OFFICE.

NAPOLEON DU BRUL, OF CINCINNATI, OHIO, ASSIGNOR TO THE MILLER, DU BRUL AND PETERS MANUFACTURING COMPANY, OF CINCINNATI, OHIO, A CORPORATION OF OHIO.

ROTARY KNIFE-GRINDER.

1,077,338.

Specification of Letters Patent.

Patented Nov. 4, 1913.

Application filed September 11, 1912. Serial No. 719,881.

To all whom it may concern:

Be it known that I, NAPOLEON DU BRUL, a citizen of the United States, and a resident of Cincinnati, in the county of Hamilton and State of Ohio, have invented certain new and useful Improvements in Rotary Knife-Grinders, of which the following is a specification.

This invention relates to devices for grinding circular knives which rotate in performing their function, as for example the severing knives of continuous cigarette machines, in order to maintain their edges in proper condition; and more particularly to that type of such knives, in which there is a reciprocating movement of the knife (straight line, orbital, or both) incident to its cutting stroke.

One object of the invention is to grind the blade on both faces, but to develop the greater portion of the grinding on one face, preferably at a substantial angle to the plane of the blade, and only sufficient grinding on the other side, preferably in substantially the plane of the face, to remove the bur or rough edge left by the main grinding.

Another object is to employ the reciprocation of the knife, either edgewise or axially, but preferably both, and either in a straight line or in an orbital path, but preferably both, to cause opposite faces of the knife to impinge against grinders suitably positioned to receive the respective knife faces as the knife reaches the limits of its movements.

Further objects relate to certain adjustments of the grinders, namely, an adjustment toward the axis of the knife to compensate for wearing away of the knife incident to continued grinding; an adjustment of the grinder toward the knife face to be ground in order to develop exactly the grinding pressure desired; and an adjustment of the grinder in angular relation to the blade in order to determine the bevel of the main grinding.

The invention will be fully understood upon reference to the accompanying drawings which disclose one embodiment of the several features of the present invention by way of illustration, and in which:

Figure 1 is a plan view of an orbital knife severing device for subdividing a rod fed continuously past the cutting point, and hav-

ing the present invention applied thereto. Fig. 2 is a detail plan view of the two grinders shown in Fig. 1. Fig. 3 is a section on the line 3—3 of Fig. 1. Fig. 4 is a rear end view of Figs. 1 and 2. Fig. 5 is a detail view of the mounting for the grinder in elevation. Fig. 6 is a vertical section of the same in a plane parallel to Fig. 5. Fig. 7 is a vertical section of the same in a plane perpendicular to Figs. 5 and 6. Fig. 8 is a detail view of the mounting for the second grinder. Fig. 9 is a horizontal section of parts shown in Fig. 7.

Referring more particularly to Figs. 1, 3 and 4, 1 represents a circular knife journaled on the crank 2 of a shaft 3 which is rotated through the pinion 4 from any suitable source, to cause the knife 1 to periodically intersect the severing tube 5 through which a continuous rod is being fed. By a cam 6 on the shaft 3, engaging between studs 7 on a fixed part the shaft 3 is given an axial reciprocation which coincides with the feed of the rod so long as the knife is intersecting the tube. Thus the knife has reciprocation, both axially and orbitally. These parts constitute the invention of another.

In order to keep the circular knife sharp, its edge should be ground more or less constantly. For this purpose a grinder 8 is located in position to be impinged against by the knife as the latter reaches the end of its throw. This grinder assumes a position at a substantial angle to the plane of the knife so as to maintain a bevel for obvious reasons. But grinding the edge from one side develops a bur or roughness which would seriously interfere with the sharpness of the knife. Hence I employ a second grinder 9 located in position to be impinged by the opposite face of the knife when at the outer limit of its reciprocation, since the grinder 9 need only grind the knife sufficiently to remove the bur it is placed substantially parallel to the knife. A pair of grinders are thus provided, against which the respective faces of the knife reciprocate. The grinder 9 is slightly in the advance of the grinder 8 for the reason that the knife has moved forward when it has reached that end of its throw.

As will hereinafter appear the mounting

10 for main grinder 8 is adjustably anchored to the machine bed 11 by a tie bolt 12 entering slot 12^a in said bed whereas the second grinder mounting 13 is adjustably secured to the bed 11 by clamping bolt 14 entering slot 14^a in the mounting 13. Each grinder is thus adjustable toward the axis of the knife to compensate for gradual reduction in the diameter of the knife.

10 The main grinder 8 is mounted upon a shaft 15 journaled in bushing 16 which is fitted to slide axially in the mounting 10 and has an arm 17 working in a slot 18 in said mounting to prevent the bushing rotating, 15 while a screw 19 shouldered in a lug 20 on the mounting, is threaded into the arm 17, and thus provides for adjusting the grinder to or from the knife and therefore regulating the grinding pressure at will. A set 20 screw 21 firmly locks these parts at their adjustment. Similarly, the secondary grinder 9 is mounted on shaft 15^a journaled in sleeve 16^a fitted to slide axially in the mounting 10, and having an arm 17^a working in slot 18^a in said mounting to prevent the bushing rotating, while screw 19^a shouldered in lug 20^a on the mounting, is threaded in the arm 17^a to provide for adjusting the grinding pressure of the secondary grinder 25 to a nicety. Set screw 21 holds these parts in their adjustment.

The primary grinder has one other adjustment, namely to change its angular relation to the plane of the knife, for which purpose its mounting is divided into the base 10^b and head 10^b, fixed coaxially by a vertical trunnion 22 (Figs. 6 and 7) on the head depending into the socket 23 on the base and adapted to be locked against separation as 30 well as against displacement from the angular adjustment, by the set screw 24.

To drive the grinders, any suitable connection may be employed. I have herein shown a shaft 25, which may be the main shaft of the machine; large pulleys 26, 26^a on said main shaft; driven pulleys 27, 27^a carried by short shafts 28, 28^a and belted to pulleys 26, 26^a; transmitting pulleys 29, 29^a on said short shafts; and pulleys 30, 30^a on the 45 grinder shafts 15, 15^a and belted to the pulleys 29, 29^a. Shafts 28, 28^a are mounted to be adjusted in order to maintain the distance between the pulleys 29—30, and 29^a—30^a notwithstanding adjustments in the 50 grinder mountings, and also to keep the belt taut, as for instance by mounting the shaft 28 in the angularly adjustable arm 31 on the main shaft, or by mounting the shaft 28^a upon the arm 32 which projects outward from and is adjustably bolted at 33 to the machine frame or bed 11 as shown in Figs. 55 1 and 3.

I claim:

1. In combination with a mounting for a 60 rotary machine knife having a reciprocation

in a transverse direction relative to the axis of the knife, a pair of grinders positioned to be impinged against by opposite faces of the knife when said knife is being reciprocated by said mounting.

2. In combination with a mounting for a machine knife, said mounting having reciprocations during operation in two directions perpendicular to each other, a pair of grinders respectively located to be impinged against by a knife on said mounting, said knife partaking of said reciprocations.

3. In combination with a mounting for a machine knife having an edgewise orbital movement and an axial reciprocation in the plane of an axis of its orbit; a pair of grinders located at the ends of the said orbital axis and offset in the said orbital plane, by the distance of the said axial reciprocation, whereby the said grinders are impinged against by the respective outer faces of the said knife as when at the limit of the said movements.

4. In combination with a mounting for a machine knife having a reciprocating movement during operation, a pair of grinders located to be impinged against by the respective outer faces of said knife by the reciprocation of said mounting; the grinding face of one of said grinders being held at a substantial angle to the plane of the knife, whereby it grinds a bevel at the edge, and the other having its grinding faces substantially parallel to the plane of the knife; means being provided to rotate each of said grinders, and one of said grinders being rotated more rapidly than the others.

5. In combination with a mounting for a machine knife having a reciprocating movement, a pair of grinders positioned to be impinged against by opposite faces of the knife, in the reciprocation of said mounting; both of said grinders being adjustable toward the axis of said knife.

6. In combination with a reciprocating mounting for a machine knife having a reciprocating movement during operation; a pair of grinders positioned to be impinged against by opposite faces of the knife, in the reciprocation of said mounting; means being provided to advance a grinder toward the axis of the knife, as the knife reduces in diameter and also to adjust the grinder toward the knife-face which it grinds.

7. In combination with a reciprocating mounting for a rotary knife, a grinder having adjustment toward the axis of the knife, an adjustment toward the knife-face which it grinds and adjustment in an angular relation to the plane of the knife.

8. In combination with a mounting for a rotary knife having a reciprocating movement during operation; a rotary grinder located to be impinged against by said knife, in its reciprocation; said grinder having a

mounting comprising a base and a head in which the grinder is journaled, connected to said base through means of a vertical trunnion.

- 5 9. In combination with a mounting for a rotary knife having a reciprocating movement; a rotary grinder located to be impinged against by said knife, in its reciprocation; said grinder having a mounting comprising a base and a head in which the grinder is journaled, connected to said base through means of a vertical trunnion; there being a bed on which the grinder mounting is adjustably supported, and a tie bolt extending through said bed and through both the base and head of said grinder mounting.
- 10 10. In combination with a reciprocating mounting for a rotary knife, having a rotary grinder against which said knife is adapted to impinge, and a mounting for said grinder comprising a shaft, a bushing in which said shaft is journaled, a head in which said bushing is fitted with axial movement, and a set screw for axially adjusting the bushing in the head; said bushing having a radial arm fitting a lateral opening in the head, and in which the adjusting screw is threaded, and said head having a lug in which the screw is shouldered with freedom of rotation.
- 15 20. In combination with a reciprocating mounting for a rotary knife, having a rotary grinder against which said knife is adapted to impinge, and a mounting for said grinder comprising a shaft, a bushing in which said shaft is journaled, a head in which said bushing is fitted with axial

movement, and a set screw for axially adjusting the bushing in the head.

11. In combination with a reciprocating mounting for a rotary knife, a rotary grinder against which said knife is adapted to impinge, and a mounting for said grinder comprising a shaft, a bushing in which said shaft is journaled, a head in which said bushing is fitted with axial movement, and a set screw for axially adjusting the bushing in the head; said bushing having a radial arm fitting a lateral opening in the head, and in which the adjusting screw is threaded, and said head having a lug in which the screw is shouldered with freedom of rotation.

The foregoing specification signed at Cincinnati Ohio this twenty-sixth day of August, 1912.
